UNITED STATES PATENT OFFICE.

FRANKLIN B. MILLER, JR., OF SPRINGFIELD, MASSACHUSETTS, ASSIGNOR TO
JEROME W. HYDE, OF SPRINGFIELD, MASSACHUSETTS.

FUR-SEWING MACHINE.

988,278.

Specification of Letters Patent. Patented Mar. 28, 1911.

Application filed April 3, 1908. Serial No. 424,940.

To all whom it may concern:

Be it known that I, FRANKLIN B. MILLER, Jr., a citizen of the United States of America, residing at Springfield, in the county of 5 Hampden and State of Massachusetts, have invented new and useful Improvements in Fur-Sewing Machines, of which the following is a specification.

This invention relates to improvements in 10 sewing machines and particularly in machines for sewing fur.

The objects of the invention are,—I, to 15 simplify the construction over machines now in use; II, to increase its efficiency during operation, and III, to improve the quality of its work.

With these objects in view the invention 20 will be fully described in the specification and particularly pointed out in the appended claims.

In the drawings forming part of this application,—Figure 1 is a top plan view with the upper portion of the casing removed showing the general arrangement and location of the operative parts of the machine and particularly the means for operating the 25 looper-shaft or bar. Fig. 2 is a vertical longitudinal sectional view on line 2—2, Fig. 1, showing in side elevation the eccentric 30 means for operating the needle-bar and looper-frame rod and means for imparting a vertical movement to the looper-frame, also the step-by-step feed-operating mechanism for the fur-feeding disks. Fig. 3 is a 35 vertical sectional view on line 3—3 of Fig. 2 showing the eccentrics on the main shaft for imparting a reciprocating motion to the needle-bar, looper-frame rod or bar and the cam for rocking the looper-shaft and the 40 eccentric for actuating the feed mechanism. Fig. 4 is a vertical section on line 4—4 of Fig. 1 showing clearly in side elevation the cam and lever construction for imparting a 45 rocking motion to the looper-shaft proper. Fig. 5 is a detail view of the operating means for the feed-wheels.

Referring to the drawings in detail, α designates the main frame or casting of the machine in which is mounted the main drive-shaft b in the oppositely extending bearings c and d . The usual pulley and hand-wheels e and f are secured on the opposite ends of the shaft b .

Suitably secured to the drive-shaft b , as

by set-screws, are the eccentrics g and h for 55 operating the looper-frame rod or bar i and the needle-bar j respectively. Also secured to the drive-shaft b is a cam-wheel k for imparting a rocking movement to the looper-shaft and looper-arm, while a third eccentric 60 m is secured to the shaft b for actuating the feeding mechanism, as will be more fully described in referring to the operation and function of the various elements of the machine.

Secured to the looper-frame rod or bar i is a collar n that is integrally connected to the yoke-arms p and q which, at their lower ends, engage the eccentric g , as clearly shown in Fig. 2. The lower ends of the yoke-arms p and q are connected or joined together by means of the strap r so that when the drive-shaft b is rotated a reciprocating motion will be imparted to the looper-frame rod or bar i which has a bearing at s and t in the main 75 casing.

Secured to the end of the bar i is a head-piece u that has an upwardly extending portion u^1 and to which portion is pivotally connected at the point w the looper-frame or 80 casting proper designated at v .

x designates a bearing element or screw with which engages the lower end of a lever z , the same being slotted, as indicated at 85 2. The upper end of the lever z is connected to a short link 3 , by means of the pivot 4 , and the link 3 is pivotally connected to the looper-frame v at the point 5 . The lever z is pivotally mounted between its ends by means of a stud 6 which has a pivotal bearing 90 in the frame of the machine, as clearly shown in the plan view in Fig. 1, in the bracket 6^1 . As a result of this construction, when the main shaft b is rotated and the yoke-arms p and q receive a reciprocating 95 movement, the lever z will rock about its pivot 6 and cause, by means of the connecting link 3 , a vertical movement about the pivot w to be imparted to the looper-frame v simultaneously with the reciprocating movement of the rod i to which said frame is 100 connected, as already described.

Referring now to the eccentric h and its associated parts: the yoke surrounding this eccentric is provided with two arms, only 105 one of which appears at 7 on the drawing. This yoke is the same in construction as the yoke-arms p and q . The upper ends of the

aforesaid two arms are connected to a sleeve or bracket 9 which is secured to the needle-shaft *j* by means of the set-screw 10. It is obvious that when the main drive-shaft *b* 5 rotates, the needle-bar *j* will be reciprocated in the frame of the machine in the usual manner, and in unison with the looper-frame and looper-shaft. The end of the needle-bar is provided with a needle-clamp 12, the 10 details of which construction form no part of the present invention.

Referring now to the cam-wheel *k*, which is secured to the shaft *b*, and the parts associated therewith: this wheel is provided in 15 one face thereof with the cam-groove 13 for receiving the roller 14 that is mounted on the lower arm 15 of the bell-crank lever which is pivoted to the framework *a* on the pin 16, the upper or longer arm 17 of the 20 lever being provided with a slotted end portion 18 for receiving the spherical ball or end portion 19 of the arm 20 of the sleeve 20¹ which is secured to the rocking looper-shaft 21 by means of the set-screw 20², said shaft 25 having bearings at *v*¹ and *v*², which are a part of the looper-frame *v*. The purpose of this construction is to impart a rocking movement to the looper-finger 22 which is connected to the part 20³ by means of the 30 screw 20⁴ and simultaneously with the vertical and reciprocating movements of the looper-frame *v*. The part 21¹ designates a looper socket riveted to the looper-shaft 21, as designated at 22¹.

35 Referring now to the feed mechanism for operating the fur feeding wheels 23 and 24: an eccentric strap 25 surrounds the eccentric *m* which is secured to the shaft *b* and has a link 26 extending therefrom which is pivotally 40 attached to an arm 27 at the point 28, which is clearly shown in side elevation in Fig. 2, and in edge elevation in Fig. 3. The arm 27 is carried by the shaft 29 that is pivotally mounted on the pivot-points 30 45 and 31 adjustably locked in the side portions of the frame *a* by the set-nuts 32, 33.

Pivottally mounted on the shaft 29 by means of the screw 34 is a cam-shaped piece 35 which is for the purpose of imparting a 50 rocking movement to the lever 36 that is provided with a head 37 and on which is mounted an anti-friction roller 38. The lever 36 is provided with friction blocks 39 and 40 which engage the rim 41 of the friction-wheel 42. The lever or arm 36 is pivoted at 36¹ about the shaft 43 and on a hub 42¹ of the wheel 42. The wheel 42 is mounted on the lower end of the shaft 43 and carries at its upper end the feed-wheel 23. 60 The shaft 43 is mounted in bearings 44 and 45 that are cast integral with the frame *a*.

The friction-blocks 39 and 40 are friction-engaging elements which engage opposite sides of the rim 41 of the wheel 42, and the 65 rim of the wheel is gripped by the blocks

39 and 40 when the lever 36 is rocked in one direction, but the friction-blocks will drag on the rim 41 of the wheel 42 when the lever is rocked in an opposite direction. The space or groove in the friction-blocks 39 70 and 40 are slightly inclined to the rim 41 of the wheel 42 so as to permit the gripping and drag effect of the blocks on the rim. The rocking effect of the lever 36 and blocks 39 and 40 therefore impart a step-by-step movement to the wheel 42. The wheel 42 is provided with a hub 42¹ and over this hub fits a hub 36¹ integral with the lever 36. It will be observed that the blocks 39 and 40 have inclined slots or openings 39¹ and 40¹ 80 cut therein so as to grip the rim 41 in one direction of the lever 36 and permit the lever and blocks 39 and 40 to drag on the rim 41 of the wheel 42 in the opposite direction. The arrow on Fig. 5 clearly indicates 85 the direction of rotation of the wheel 42. A spring 36³ serves to maintain the roller 38 in contact with the cam 35 and at all times the springs 39² and 40² serve to maintain the blocks 39 and 40 in contact with the 90 notches 36⁴ of the hub of the lever 36; and pins 36⁵ are provided for attaching the other end of the springs. From this construction it is clear how the wheel 42 is propelled in a step-by-step movement.

95 Secured to the frame *a* is a bracket 46 in which is cut or milled an inclined slot 47 one edge of which is provided with teeth or serrations 48. Extending through this slot is an arm 49 secured to a rod 50 that 100 extends longitudinally through the shaft 29 and has its inner end 51 in engagement with the cam element 35. This rod extends loosely through the bearing 31 whereby when the arm 49 is moved the rod 50 is advanced or retracted from the cam element 35 and is at the same time locked in its various positions by means of the serrations or teeth 48. A spring 52 is mounted between the nut 33 and the arm 49 105 for the purpose of maintaining the lever 49 in its locked position. The purpose of this construction is to vary the amount of movement on the lever 36 which drives the feed-wheel 23, whereby the feed or angular movement thereof is varied.

110 The wheel 24, (which is normally held in engagement with the wheel 23) is mounted on the lower end of the arm 53 that extends downward, as indicated at 54, and has an 115 outwardly projecting portion or arm 55 that is secured to the bearing piece 56 which is integral with the lever 57. This lever is pivoted to the frame of the machine at 58, and is normally held downward by means 120 of the compression spring 59 that encircles the rod 60 mounted in the bracket 61. The effect of the spring 59 is to normally hold the wheel 24 in engagement with the wheel 23, whereby the fur is clamped and fed be- 125 130

tween the serrated or milled edges of the wheels 23 and 24 in the well known manner.

What I claim, is:—

1. The combination with the drive-shaft 5 of a sewing machine, a pivotally mounted looper-frame, an eccentric on said shaft, yoke-arms engaging the said eccentric, a lever connected to the yoke-arms, a link connecting said lever and the looper-frame, 10 whereby a vertical movement may be imparted to said looper-frame, substantially as described.

2. A fur sewing machine having in combination, a main shaft, a bar, an eccentric 15 on the main shaft, means connected with the eccentric and bar for reciprocating the same, a looper-frame actuated by the bar, and a link connection between the eccentric and the frame, whereby the frame is moved 20 in a vertical plane simultaneously with the reciprocating movement thereof.

3. A fur-sewing machine having in combination, a frame, a main-shaft, a rock-shaft pivotally mounted in the sides of the frame, 25 a cam element pivotally mounted on the rock-shaft, a rod axially arranged with relation to the rock-shaft, and engaging the

cam element, and means for adjusting and locking said rod.

4. A fur-sewing machine having in combination, 30 a frame, a main-shaft, a rock-shaft pivotally mounted in the sides of the frame, a cam element pivotally mounted on the rock-shaft, a rod axially arranged with relation to the rock-shaft and engaging the 35 cam element, and means for adjusting and locking said rod, including a bracket element having an inclined slot therein, a spring on the rod, and a handle member 40 engaging the slot, as described.

5. The combination with the drive-shaft of a sewing machine, a looper-shaft, a looper-frame pivoted thereto, an eccentric on said shaft, yoke-arms engaging said eccentric and connected to the looper-shaft, a lever 45 connected to the yoke-arms, a link connecting said lever and looper-frame, whereby simultaneous reciprocating and vertical movements will be imparted to the looper-frame, substantially as described.
